(57) **CLAIM**

The ornamental design for a ball thrower, as shown and described.

DESCRIPTION

FIG. 1 is a perspective view of the ball thrower having a throwing end for a ball and a reserve end for another ball; FIG. 2 is a front view of the ball thrower; FIG. 3 is a rear view of the ball thrower; FIG. 4 is a first side view of the ball thrower; FIG. 5 is a second side view of the ball thrower; FIG. 6 is a view of the throwing end of the ball thrower; FIG. 7 is a view of the reserve end of the ball thrower; and FIG. 8 is a view of the ball thrower in a collapsed configuration.

FIG. 9 is a perspective view of a second embodiment of the ball thrower having a throwing end for a ball and a reserve end for another ball;

FIG. 10 is a front view of the second embodiment of the ball thrower;

FIG. 11 is a rear view of the second embodiment of the ball thrower;

FIG. 12 is a first side view of the second embodiment of the ball thrower;

FIG. 13 is a second side view of the second embodiment of the ball thrower;

FIG. 14 is a view of the throwing end of the second embodiment of the ball thrower;

FIG. 15 is a view of the reserve end of the second embodiment of the ball thrower; and,

FIG. 16 is a view of the ball thrower of the second embodiment in a collapsed configuration.

The broken lines shown are for illustrative purposes only and form no part of the claimed design.
